G. E. McFADDEN

PLATE FOR LIGHTING FIXTURES

Filed Oct. 14, 1922

FIG. 1

FIG. 2

Glenn E. McFadden INVENTOR

By Rockwell & Ross, his ATTORNEYS

UNITED STATES PATENT OFFICE.

GLENN E. McFADDEN, OF LAKEWOOD, OHIO, ASSIGNOR TO ALFRED VESTER SONS, INC., OF PROVIDENCE, RHODE ISLAND, A CORPORATION OF RHODE ISLAND.

DESIGN FOR A PLATE FOR LIGHTING FIXTURES.

Application filed October 14, 1922. Serial No. 3,969. Term of patent 14 years.

To all whom it may concern:

Be it known that I, GLENN E. McFADDEN, a citizen of the United States, and residing at Lakewood, in the county of Cuyahoga and State of Ohio, have invented a new, original, and ornamental Design for a Plate for Lighting Fixtures, of which the following is a specification, reference being had to the accompanying drawing, forming part thereof.

Fig. 1 is a front view of a plate for lighting fixtures, showing my new design;

Fig. 2 is a side view of the same.

I claim—

The ornamental design for a plate for lighting fixtures, as shown.

GLENN E. McFADDEN.
